CLAIM

The ornamental design for hand grip bottle, as shown and described.

DESCRIPTION

FIG. 1 is a right side elevation of a hand grip bottle showing our new design;

FIG. 2 is a front elevational view thereof looking from left toward the right in FIG. 1;

FIG. 3 is a left side elevation thereof;

FIG. 4 is a rear elevational view thereof looking from the left toward the right in FIG. 3;

FIG. 5 is a partial perspective view of the hand grip portion thereof looking from the upper foreground downwardly to the left in FIG. 1;

FIG. 6 is a top plan view thereof; and,

FIG. 7 is a cross section taken horizontally through the middle of the bottle looking downward.

The bottom of the bottle does not form part of the claimed design.
